United States Patent Office.

HENRY H. ELWELL, OF SOUTH NORWALK, CONNECTICUT.

Letters Patent No. 77,264; dated April 28, 1868.

IMPROVEMENT IN REVERSIBLE KNOB-LATCH.

The Schedule referred to in these Letters Patent and making part of the same.

TO ALL WHOM IT MAY CONCERN:

Be it known that I, HENRY H. ELWELL, of South Norwalk, in the county of Fairfield, and State of Connecticut, have invented a new and improved Lock; and I do hereby declare that the following is a full, clear, and exact description thereof, which will enable those skilled in the art to make and use the same, reference being had to the accompanying drawings, forming part of this specification.

This invention relates to a new and improved lock of that class which are provided with a reversible slide-catch so arranged that it may be adjusted to suit either a right or left-hand door, that is to say, be capable of being applied to a door which swings in either direction.

The object of the invention is to obtain a lock of the kind specified which will be simple in construction, not add to the complexity and cost of construction, and which will not be liable to get out of repair, and require but a simple manipulation to adjust the slide-catch, as circumstances may require in applying the lock to the door. In the accompanying sheet of drawings—

Figure 1 is an internal view of a lock provided with my improvement.

Figure 2, a horizontal section of the same, taken in the line $z z$, fig. 1.

Figure 3, a detached view of the hub through which the knob-arbor passes.

Figure 4, a horizontal section of the lock, taken in the line $y y$, fig. 1.

Figure 5, an internal view of the lock, showing the parts in a different position from that shown in fig. 1.

Similar letters of reference indicate corresponding parts.

A represents the case of the lock, and C represents a slide-catch, the outer part of which is bevelled at one side, as shown at a , said part being attached to a spindle, b, which is fitted in a yoke, c, and allowed to turn therein, the rear of the yoke having arms, d d, projecting from it, which extend back, and have each two hooks or projections, e e', at their ends, one, e, being farther inward than the other, e', and the former, e, nearer the bevelled end of the slide-catch, (see figs. 1, 4, and 5.)

On the spindle b there is placed a spiral spring, f, which has a tendency to keep the outer bevelled part of the slide-catch out from the case A; and D represents the hub through which the knob-arbor of the lock passes, as usual.

This hub D is provided with a projection, g, which extends out from one side of it, and projects beyond from opposite points, each end of said projection being provided with a lug, h, at right angles with the ends of g, as shown clearly in fig. 3.

When the lugs h bear against the hooks e, the bevelled end of the slide-catch will have its inner part within the opening a^x , in the edge of the case, through which opening it works, and hence the bevelled end of the catch is not allowed to turn; but when the lugs h bear against the hooks e', the bevelled end of the slide-catch will be beyond the opening in the side of the case, (see fig. 5,) and said bevelled end may be turned and adjusted to suit either a right or left-hand door.

The changing of this position of the slide-catch is effected by moving the hub D in the lock-case, sufficient play being allowed it for that purpose, and in order to afford the hub a proper bearing in the case, the latter, around the hole in one side thereof, through which the hub passes, is cast with a flange, i.

In order to adjust the slide-catch outward, so that its bevelled end may be turned, the hub is shoved in the direction of arrow 1, (see fig. 2,) so that the lugs h will be free from the hooks e, and the spring f allowed to press the bevelled end of the slide-catch outward beyond the opening a^x in the edge of the case, the hooks e' catching against h.

In adjusting the slide-catch back after being turned as desired, it is simply pressed back by hand until the lugs h of the projection g will drop down in front of the hooks e, and keep the inner part of the bevelled end within the opening a^x , which will prevent it from turning.

After the lock is adjusted to the door, the hub D is prevented from moving in the lock longitudinally with its axis by means of an arm, j, which projects from a bar, E, fitted within the lock-case, and having its outer end extending within the line of the holes k k, in the side of the case, through which holes one of the screws

passes, which secures the lock to the door, and when said screw is passed through said holes and screwed into the door, it keeps the bar E forced back, and the arm j in contact with the hub D, at one side of the projection g thereof.

By this means the hub D is prevented from casually moving in the direction above stated.

If necessary or desired, a spiral spring, l, may be made to bear against the bar E, to keep the arm j out from the hub D, to admit of the latter being moved to adjust the slide-catch before the lock is applied to the door.

I do not claim broadly a reversible slide-catch for locks, to admit of the latter being applied to either a right or left-hand door, for such slide-catches have been previously used; but

I do claim as new, and desire to secure by Letters Patent—

1. The hub D, when adapted to be moved longitudinally with its axis through the lock-case, to release the latch and admit of its being turned, substantially as described, for the purpose specified.

2. In combination with the sliding hub D, the flange i, surrounding the hole for the passage of the hub, upon the inside of the case, whereby said hub, when operated to release the latch, will not be displaced laterally, as herein shown and described.

3. The arm j of the bar E, arranged as shown, and in such relation with the screw-holes k as to cause, when the lock is screwed to the door, the arm j to bear against the hub D, and prevent the latter from moving longitudinally to release the slide-catch, as set forth.

HENRY H. ELWELL.
